MANUFACTURE OF HIGH OCTANE GASOLINE

Filed May 23, 1940

UNITED STATES PATENT OFFICE

2,313,660

MANUFACTURE OF HIGH OCTANE
GASOLINECharles W. Montgomery, Aspinwall, Pa., assignor
to Gulf Research & Development Company,
Pittsburgh, Pa., a corporation of Delaware

Application May 23, 1940, Serial No. 336,884

6 Claims. (Cl. 196—10)

This invention relates to the manufacture of high octane gasoline; and it is particularly concerned with an improved process of producing high octane gasoline comprising treating an iso-paraffin with an olefin in the presence of a condensation catalyst, separating the higher boiling iso-paraffins from the gasoline-like material thus formed, dehydrogenating the undesirably high boiling iso-paraffins to form iso-olefins and reacting the iso-olefins thus obtained with lower molecular weight iso-paraffins to form further quantities of high octane gasoline; all as more fully hereinafter set forth and as claimed.

Among the more recently developed methods for the production of high octane gasoline substantially free from unsaturated gum forming constituents is a method in which the lower iso-paraffins (iso-alkanes) such as iso-butane, iso-pentane and the like, are condensed with the lower olefins in the presence of a suitable catalyst such as concentrated sulfuric acid or an aluminum halide usually at or about room temperature. The initial reaction which takes place is a direct union of the iso-paraffin with the olefin to form a high molecular weight iso-paraffin; for example, iso-butane combines with a butene to form iso-octane. Secondary reactions also occur resulting in the production of both higher and lower hydrocarbons. The end-product is a mixture of higher and lower hydrocarbons boiling substantially within the gasoline range, having a high octane rating and being substantially free from unsaturates. When the process is carried out in batch operation about 20 per cent of the end-product boils above the ordinary gasoline range, that is above about 185° C., and it consists essentially of higher boiling iso-paraffins. In a continuous process there is usually only a small percentage of iso-paraffins boiling above this point.

The gasoline product obtained by this process is particularly suitable for use as an aviation gasoline because of its high octane rating and its freedom from gum forming constituents. A particularly good "fighting grade" aviation gasoline suitable for use in military and naval airplane motors can be obtained by taking the fraction of these products boiling up to 165° C. When fighting grade aviation gasoline is produced, about 25 per cent of the product of a continuous alkylation process boils above the 165° C. end-point and a correspondingly increased proportion of the product obtained by a batch process boils above this end-point.

I have now discovered that these higher boil-

ing iso-paraffins forming the fraction of the alkylation reaction product boiling above 165° C. react relatively slowly with olefins but that by dehydrogenating them to form iso-olefins and reacting the high molecular weight iso-olefins thus obtained under the conditions of the alkylation reaction, with short chain iso-paraffins, further quantities of mixed saturated hydrocarbons boiling within the gasoline range can be produced.

10 In carrying out the method of my invention I first alkylate an iso-paraffin, usually an iso-paraffin containing four to six carbon atoms, with an olefin by passing a mixture of gases containing the olefin in suitable proportion into a mixture of the iso-paraffin and a catalyst such as concentrated sulfuric acid or aluminum chloride at or about room temperature, usually under pressure. The ratio of iso-paraffin to olefin is advantageously maintained at a relatively high 15 level in order to avoid polymerization of the olefin. Iso-paraffin to olefin ratios of between 2:1 and 10:1 have proved satisfactory.

15 The choice of catalyst depends usually on the olefin with which the reaction is carried out. 20 When lower olefins such as ethylene or propylene are used it is generally desirable to use an aluminum halide catalyst such as aluminum chloride. These lower olefins, particularly ethylene, are comparatively unreactive and it is difficult to effect alkylation with them. However, the aluminum halide catalysts are sufficiently powerful to effect the desired reaction. In most other cases it is advantageous to use concentrated sulfuric acid as the catalyst. Most satisfactory results 25 are obtained using 85.0 to 98.0 per cent sulfuric acid.

30 The alkylation reaction may be carried out either in batch or continuous operation. In most cases it has been found advantageous to 35 introduce the olefin into a rapidly agitated mixture of the catalyst and the iso-paraffin in an autoclave at a temperature between about -10° and 50° C., advantageously 20° C., under pressure sufficient to maintain the reaction mixture in the liquid state. In continuous operation, contact times of 0.5 to 30.0 minutes may be used depending on the particular olefins involved in the reaction.

40 The reaction product is then separated from the catalyst and washed with dilute aqueous alkali solution to remove acid and acid-forming components. The washed product is fractionally distilled and the fraction boiling within the 45 normal gasoline boiling range is collected. For

fighting grade aviation gasoline the end-point used is usually about 165° C.

According to the method of my invention, the higher boiling iso-paraffins remaining after the desired gasoline fraction has been recovered from the alkylation product are dehydrogenated to form iso-olefins. These residual iso-paraffins are generally those containing nine or more carbon atoms. They react only very slowly with the olefins. However, when they are dehydrogenated to form iso-olefins the high molecular weight iso-olefins thus obtained react quite readily with low molecular weight iso-paraffins, in the alkylation reaction as above set forth, to form additional quantities of gasoline boiling within the desired range.

The dehydrogenation of the residual iso-paraffins may be carried out by various known methods. One method which I have found suitable for this purpose is to contact the iso-paraffin with a catalyst such as chromic oxide gel at a temperature of 400° to 600° C. Other catalysts may also be used for this dehydrogenation such as the oxides of molybdenum, tungsten, and vanadium. Dehydrogenation activity of these catalysts is usually promoted by supporting the oxides on activated alumina which also serves to increase the contact area. The materials employed as catalysts for the dehydrogenation are also effective catalysts for aromatization of the paraffins containing more than six carbon atoms. However, the iso-paraffins undergo this type of reaction relatively slowly so that by limiting the time of contact of the iso-paraffins with the catalyst the extent of all reactions except dehydrogenation can be greatly reduced. This may also be accomplished by employing less active catalysts as for example by reducing the content of chromic oxide in an activated alumina supported chromic oxide catalyst preferably below 5 per cent, or even by employing activated alumina alone without any addition of heavy metal oxides. Activated alumina by itself appears to produce considerably less aromatization than chromic oxide on alumina.

In carrying out the dehydrogenation step, the heavy iso-paraffins boiling above the desired end-point of the aviation gasoline are first separated by appropriate fractionation. They are then pumped through a suitable heat exchanger, vaporized in a preheater and passed into the dehydrogenation reactor which may be packed, for example, with activated alumina pellets as such or supporting 1 to 5 per cent chromic oxide. The reaction zone is preferably maintained at about 500° to 600° C. in case alumina is used alone as the catalyst, or at somewhat lower temperatures, say 400° to 500° C. when supported heavy metal oxides are employed. The optimum contact time in the reactor will, of course, vary with the activity of the catalyst but will usually be found to lie in the range 1 to 20 seconds. Pressure is advantageously maintained at 1 to 4 atmospheres. Operation under these conditions has been found to yield predominately iso-olefins (15 to 30 per cent per pass) with considerably smaller amounts (1 to 3 per cent per pass) of aromatics.

The high molecular weight iso-olefins thus obtained are then treated with further quantities of low molecular weight iso-paraffins in the presence of sulfuric acid or other alkylation catalyst and an additional quantity of gasoline is recovered as before from the reaction product.

Thus by the method of my invention, larger

amounts of gasoline suitable for use in airplane motors are recovered from a given amount of raw material than has heretofore been obtainable.

5 In the accompanying drawing there is illustrated schematically a suitable apparatus for carrying out the method of my invention. In this apparatus there is provided alkylator 10 into which the isoparaffin charge is introduced through conduit 11 in admixture with the catalyst from conduit 12. The olefin containing charge is introduced into the top of the alkylator 10 through conduit 13. The alkylation reaction between olefin and isoparaffin is effected with vigorous agitation in the alkylator 10. The alkylate from alkylator 10 is conducted by conduit 14 to separator 15 where the catalyst is settled out and recycled through conduit 16 to conduit 12 and the alkylator 10.

10 The alkylate from separator 15 is carried by conduit 17 to alkali washer 18 where any remaining acid catalyst is removed. The washed alkylate is then conducted by conduit 19 to fractionating column 20 where the unreacted excess isoparaffins are distilled off and recycled through conduit 21 to conduit 11 and reintroduced into the alkylator. The alkylate from the bottom of column 20 is conducted by conduit 22 to a second fractionating column 23 where the gasoline fraction is distilled off through conduit 24 and recovered. The heavy isoparaffin bottoms from column 23 are conducted through conduit 25 to heat exchanger 26 and conduit 27 to heater 28 where they are heated and vaporized.

15 The isoparaffin vapors are conducted from heater 28 through conduit 29 to the dehydrogenator 30 where they are contacted with the dehydrogenating catalyst. The dehydrogenation reaction products are conducted by conduit 31 to gas separator 32 where the hydrogen is separated and recovered through conduit 33. The high boiling olefins resulting from the dehydrogenation of the heavy isoparaffin are drawn off from gas separator 32 through conduit 34 and are introduced into alkylator 35 where they are mixed with fresh isoparaffin charge, and catalyst from conduit 37, introduced into alkylator 35 through conduit 36. The alkylate formed is drawn off through conduit 38 to separator 39 where the catalyst settles out and is returned through conduit 40 to conduit 37. The alkylate is conducted through conduit 41 to caustic washer 42 where residual catalyst is removed. The alkylate is then introduced into fractionating column 44 through conduit 43 and the unreacted isoparaffin is taken off overhead and recycled to the alkylator 35 through conduits 45 and 36. The remaining alkylate is drawn off through conduit 46 to fractionating column 47 where additional gasoline is taken off overhead through conduit 48 and recovered. The heavy isoparaffin bottoms are recycled from fractionating column 47 through conduit 49 to conduit 25 where it is reintroduced into the dehydrogenation step of the process.

20 In an alternative form of this apparatus the high boiling olefins from conduit 34 are recycled directly to the first alkylator 10. In such case the second alkylator 35 and succeeding apparatus are omitted. The operation of this form of apparatus is, however, somewhat more difficult to control.

25 The following specific example illustrates one embodiment of my invention in which iso-butane is alkylated with debutanizer gas contain-

ing a mixture of C₄ hydrocarbons including butane, butene-1, butene-2, and iso-butylene.

Iso-butane was alkylated with debutanizer gas of such composition that the total iso-butane-butene volume ratio was about 4:1. Sulfuric acid of 98 per cent strength was used in a continuous unit and the temperature was maintained at 18° C. A yield of debutanized alkylate equal to 165 volume per cent of the charged butenes was obtained, 75 volume per cent of which boiled below 165° C. The 25 per cent heavy ends were dehydrogenated over alumina, in the manner described above, at 550° C., atmospheric pressure, and 10 seconds contact time. A 97 volume per cent recovery was obtained, the product analyzing 20 per cent olefins. This material was used to alkylate fresh isobutane using an isobutane-olefin volume ratio of approximately 5:1. Fractionation of the debutanized product yielded an additional amount of 165° end-point aviation gasoline equal to 131 volume per cent of the iso-olefins produced in the dehydrogenation step.

While my invention has been described herein with respect to certain specific embodiments thereof by way of example, I do not intend that my invention shall be limited to such embodiments or the details thereof except as herein-after defined in the appended claims.

What I claim is:

1. A process of producing high octane gasoline comprising alkylating an iso-paraffin with an olefin in the presence of an alkylation catalyst, washing the reaction product with dilute aqueous alkali to remove acidic and acid-forming constituents, separating the higher boiling iso-paraffins from the hydrocarbons boiling in the gasoline range by fractional distillation of the washed reaction product, dehydrogenating the higher boiling iso-paraffins thus obtained to form iso-olefins and alkylating these iso-olefins with further quantities of lower boiling iso-paraffins in the presence of an alkylation catalyst to form additional amounts of hydrocarbons boiling in the gasoline range.

2. In a process of alkylating an iso-paraffin with an olefin in the presence of an alkylation catalyst, the steps comprising dehydrogenating a high boiling iso-paraffin thus obtained to form an iso-olefin and alkylating the iso-olefin thus formed with an iso-paraffin in the presence of an alkylation catalyst.

3. In a process of producing high octane gasoline by alkylating an iso-paraffin with an olefin

in the presence of an alkylation catalyst, the improvement comprising separating the higher boiling iso-paraffins from the fraction of the reaction product boiling within the gasoline range, dehydrogenating these higher iso-paraffins to form iso-olefins and alkylating the iso-olefins thus formed with lower boiling iso-paraffins in the presence of an alkylation catalyst to form further quantities of hydrocarbons boiling within the gasoline boiling range.

4. A process of producing high octane gasoline comprising alkylating an iso-paraffin with an olefin in the presence of a concentrated sulfuric acid, washing the reaction product with dilute aqueous alkali to remove acidic and acid-forming constituents, separating the higher boiling iso-paraffins from the hydrocarbons boiling in the gasoline range by fractional distillation of the washed reaction product, dehydrogenating the higher boiling iso-paraffins thus obtained to form iso-olefins and alkylating these iso-olefins with further quantities of lower boiling iso-paraffins in the presence of a concentrated sulfuric acid to form additional amounts of hydrocarbons boiling in the gasoline range.

5. A process of producing high octane gasoline comprising alkylating an iso-paraffin with an olefin in the presence of aluminum chloride, washing the reaction product with dilute aqueous alkali to remove acidic and acid-forming constituents, separating the higher boiling iso-paraffins from the hydrocarbons boiling in the gasoline range by fractional distillation of the washed reaction product, dehydrogenating the higher boiling iso-paraffins thus obtained to form iso-olefins and alkylating these iso-olefins with further quantities of lower boiling iso-paraffins in the presence of aluminum chloride to form additional amounts of hydrocarbons boiling in the gasoline range.

6. A process of producing aviation grade gasoline comprising alkylating an iso-paraffin with an olefin in the presence of an alkylation catalyst, fractionating the alkylation products to form gasoline boiling below about 165° C. and a higher boiling iso-paraffin fraction, dehydrogenating the high boiling iso-paraffins thus separated to form high molecular weight iso-olefins, and alkylating said iso-olefins with further quantities of a lower boiling iso-paraffin to form additional amounts of hydrocarbons boiling in the aviation gasoline boiling range.

CHARLES W. MONTGOMERY.
